(57) CLAIM

The ornamental design for a carrier tape, as shown and described.

DESCRIPTION

FIG. 1 is a top plan view of a carrier tape showing my new design;

FIG. 2 is a front elevational view of FIG. 1;

FIG. 3 is a rear elevational view of FIG. 1;

FIG. 4 is a bottom plan view of FIG. 1;

FIG. 5 is a right side elevational view of FIG. 1;

FIG. 6 is a left side elevational view of FIG. 1;

FIG. 7 is a sectional view taken along the line 7—7 of FIG. 1;

FIG. 8 is a sectional view taken along the line 8—8 of FIG. 1;

FIG. 9 is a sectional view taken along the line 9—9 of FIG. 1;

FIG. 10 is a sectional view taken along the line 10—10 of FIG. 1;

FIG. 11 is an enlargement of the left hand corner of FIG. 7;

FIG. 12 is an enlargement of the right hand corner of FIG. 7;

FIG. 13 is an enlargement of the right hand corner of FIG. 9; and,

FIG. 14 is an enlargement of the left hand corner of FIG. 9. The broken line showing of surrounding carrier tape structure is for illustrative purposes only and forms no part of the claimed design.
